Primary Examiner — David Muller*Assistant Examiner* — Nathan Johnston(74) *Attorney, Agent, or Firm* — Saliwanchik, Lloyd & Eisenschenk(57) **CLAIM**

The ornamental design for a urinary bag cover and support, as shown and described.

DESCRIPTION

FIG. 1 is a front elevation view of the first embodiment of a urinary bag cover and support.

FIG. 2 is a rear elevation view thereof.

FIG. 3 is a front elevation view thereof, with the front panel open.

FIG. 4 is a right side elevation view thereof.

FIG. 5 is a left side elevation view thereof.

FIG. 6 is a top plan view thereof.

FIG. 7 is a bottom plan view thereof.

FIG. 8 is a front elevation view of the second embodiment of a urinary bag cover and support.

FIG. 9 is a rear elevation view thereof.

FIG. 10 is a front elevation view thereof, with the front panel open.

FIG. 11 is a right side elevation view thereof.

FIG. 12 is a left side elevation view thereof.

FIG. 13 is a top plan view thereof; and,

FIG. 14 is a bottom plan view thereof.
